UNITED STATES PATENT OFFICE

2,275,717

REFRIGERATOR CAR CONSTRUCTION

Wallace E. Baillie, Chicago, Ill., assignor to Standard Railway Refrigerator Company, Chicago, Ill., a corporation of Delaware

Application September 5, 1940, Serial No. 355,499

18 Claims. (Cl. 62—17)

This invention relates to refrigerator cars used to transport perishable commodities at a predetermined temperature. The essential features of a refrigerator car are an insulated body to prevent or retard ingress of heat during warm weather and egress of heat during cold weather and a cooling means and sometimes a heating means to be used during warm and cold weather respectively.

This invention applies particularly to cars in which the cooling means, preferably containers for water ice, eutectic ice, brine or dry ice, are disposed immediately below the roof of the car. The lading is supported in spaced relation to the floor by a foraminous rack. Flues, preferably associated with the side walls of the car, communicate between the cooling means and the space under the floor rack to provide a path for the circulation of air. The path is from the cooling means downwardly through the aforementioned flues, through the space under the floor rack, upwardly through the lading compartment, thereby cooling the lading, and finally to the cooling means from where the cycle is repeated.

It is preferable to substantially enclose the refrigerant containers leaving only outlets for the cold air leading to the side wall flues and air inlets for warm air at a higher elevation than the outlets. The refrigerant containers are commonly positioned directly below the roof and near a side wall; a drip pan below a container and a partition upstanding from the drip pan cooperate with the roof and said side wall to enclose the container.

It is desirable to frequently clean or repair the refrigerant containers and the drip pans on account of the severe service imposed by railway use and by the corrosive action of salt brine which is commonly used in refrigerant containers. It is an object of the invention, therefore, to provide drip pans which may be easily and quickly removed and replaced in order to provide access to the containers and a further object to provide pans rigidly secured within the car in order to prevent leakage of liquid and excessive vibration of parts of the car.

Another object is to design the drip pan and the support therefor in such a way that the space available for the lading is not restricted. This is quite important when it is considered that some types of lading are packed in standard containers which are proportioned to fit with small clearances into a standard refrigerator car.

Another object is to eliminate exposed hinges, locks and other metallic parts upon which moisture might condense. The temperature within the car is sometimes very low, and when the doors are opened, the warm and humid air enters the car and condenses upon exposed metal surfaces. The condensed moisture then drips upon the lading with consequent damage thereto.

Other objects and advantages of my invention will be apparent from the following detailed description by referring to the accompanying drawings.

In the drawings:

Fig. 1 is a transverse section of a refrigerator car embodying my invention.

Fig. 2 is an enlarged view of a portion of Fig. 1.

Fig. 3 is a section on line 3—3 of Fig. 2.

Figs. 4 and 5 are similar to a portion of Fig. 1 and show modified constructions.

Fig. 6 shows a drip pan hinged to the side wall and supported adjacent the center of the car.

Fig. 7 shows a modified type of spring.

Figs. 8—10 show modified means to support the edge of the drip pan adjacent the side wall of the car.

Fig. 11 shows a drip pan attached by spring means at both edges thereof.

Figs. 12 and 13 are sections on lines 12—12 and 13—13, respectively, of Fig. 11.

Fig. 14 shows another modified means of supporting the edge of the drip pan adjacent the side wall of the car.

Fig. 15 is a section on line 15—15 of Fig. 14.

Figs. 16—19 show drip pans hinged adjacent the center of the car.

Fig. 20 shows a sliding hinge arrangement at the center of the car.

Fig. 21 is an elevational view of the hinge arrangement shown in Fig. 20.

Fig. 22 shows a drip pan held in place by springs interposed between the drip pan and the carlines.

Fig. 23 is a section on line 23—23 of Fig. 22.

The general parts of the refrigerator car shown are insulated roof A; side walls B; floor D; refrigerant containers E; hatches F for loading refrigerant into the containers E; side wall flues G; foraminous floor rack H and space J between the rack H and the floor D. A refrigerant container E is positioned directly below the roof A and adjacent a side wall B. A drip pan K is provided below the container E and a partition L is disposed in an upstanding position at the edge of the drip pan K. The drip pan K and the parti-

tion L cooperate with the roof A and the upper part of the side wall B to form an enclosure M around the container E, an air inlet opening N to the enclosure M being provided by spacing the partition L from the roof A. An air discharge opening P leads from the enclosure M to the flue G at a lower elevation than the air inlet opening N. Cars of this type commonly have a row of refrigerant containers E near each side wall B, which containers are spaced apart at the center of the car. The partitions L are also spaced apart to form a duct Q which communicates between the lading compartment R and openings N.

Air circulation is as follows: Air in the lading compartment R is warmed by contact with the lading and rises through the duct Q to enter the enclosing structures M through the air inlet openings N. The air is then cooled by contact with the cold refrigerant containers E and falls by reason of its lower temperature and therefore greater density through the discharge openings P and flues G to the space J whence it rises through the rack H to the lading compartment R. The above described cycle is thereafter continuously repeated.

As shown in Fig. 1, the side walls B of the car are each comprised of inner (2) and outer (3) side sills and inner (5) and outer (6) side plates. Outer posts 8 extend between and are secured to the outer plate 6 and sill 3 and the wall sheathing 9 is secured to the outer plate 6, sill 3 and posts 8. Inner posts 11 extend between the inner plate 5 and sill 2; flue sheets 12 attached to the posts 11 are provided with outwardly projecting panels 14 which cooperate with the lining 15 to form the flues G for air circulation. Carlines 17 extend between and are secured to the inner posts 11 and the refrigerant containers E are secured to the carlines by a suitable means, preferably that shown in co-pending Bonsall application Serial No. 308,535, filed December 11, 1939. The spaced apart partitions L depend from the carlines 17 and are secured thereto by the angle clips 18.

The drip pan K comprises a relatively rigid member 23, preferably wood, and a covering of waterproof veneer 25 on the upper surface thereof, which veneer is preferably light gauge metal. Battens 26 which extend crosswise of the car reinforce the drip pan K. A plurality of spaced apart supporting members 28 are secured to the car wall B, preferably to the upper part of the lining 15, and are provided with upwardly facing recesses 29. The drip pan K has secured to a marginal part thereof a strip 31 which forms a protruding part 32 with a depending end 34 arranged to nest in the upwardly facing recesses 29 of the members 28. The lining 15 preferably has a veneer 35, such as light gauge metal, on the side thereof adjacent the flue G. The upper marginal part 37 of the veneer 35 is flared toward the lading compartment R of the car and the veneer 25 of the drip pan K is bent with a depending edge 38 arranged to overlap the flared part 37 of the lining veneer 35 in spaced relation thereto. It is evident from Fig. 2 that liquid draining over the drip pan K is directed by the flared part 37 of the lining veneer 35 into the side wall flue G and cannot enter the lading compartment R of the car.

The edge of the drip pan K remote from the side wall B is attached to the partition L by any convenient means, such as the bolts 40 shown. A leaf spring 41 is secured to the drip pan K and projects upwardly therefrom. The spring 41 is

10 in contact with the bottom 43 of the refrigerant container E and is arranged to exert a downward force upon the drip pan K so as to maintain the protruding part 32 thereof engaged with the recesses 29 of the supporting members 28. The spring 41 thus keeps the drip pan K tightly positioned and the pan may be easily removed by pushing upwardly, thereby compressing the spring 41 and disengaging the protruding part 32 from the recesses 29. It is obvious that the design can be modified by attaching a spring to the refrigerant container E instead of to the drip pan K, in which case the function would be identical with that heretofore described.

15 Fig. 4 shows a modified means of attaching the drip pan K to the partition L. A clamping means 45 is hinged (44) to the partition L and has an arm 46 arranged to underlie the drip pan K. A bolt 48 is provided which may be removed when it is desired to release the drip pan K.

20 Fig. 5 shows another modified means to attach the drip pan K to the partition L. An upwardly facing hook 50 is attached to the partition L and a downwardly facing hook 51 is attached to the drip pan K. A spring, such as shown at (41) in Fig. 1, is provided between the container E and the drip pan K to hold the hooks 50, 51 in engagement. The resilient material 53, such as sponge rubber may be compressed to permit engagement of the hooks and prevents leakage of liquid between the partition L and the drip pan K.

25 Fig. 6 shows the drip pan K hinged (54) to the side wall lining 15 but it may be hinged to any part of the side wall B by any suitable type of hinge. The partition L depends from and is hinged (55) to the carline 17 so as to be swingable away from the container E. A vertical face of the partition L is recessed (56) and a strip 57 secured to the partition L overlaps the lower part of the recess 56. A downwardly facing hook 59 is attached to the drip pan K and is arranged to be hooked over the strip 57. The spring 41 interposed between the container E and the drip pan K maintains the hook 59 and the strip 57 in engaged relation; if it is desired to lower the drip pan K, the pan is pushed upwardly, thereby compressing the spring 41, and the partition L is then swung about the hinge 55 away from the container E a sufficient distance to allow the drip pan K to be swung downwardly about the hinge 54.

30 Fig. 7 shows a helical spring 65 which may be used in place of the leaf spring 41 shown in Figs. 1 and 6. The helical spring may be attached to either the drip pan K or the container E. Fig. 7 shows the spring attached to the drip pan K by a strap 66 which overlies the lowermost coil and is bolted to the drip pan K. A member 68 having an upstanding peripheral flange 69 is provided around the spring 65 to prevent the leakage of water through the drip pan K.

35 Fig. 8 shows a modified means to support the edge of the drip pan K which is adjacent the side wall B. The drip pan veneer 25 has a depending margin 73 which overlaps the lining veneer 35 in contact therewith. The drip pan K has protruding parts 74 which have ends 76 depending in spaced relation to the depending margin 73 of the drip pan veneer 25. Spaced apart supporting members 77 having upwardly facing recesses 79 are secured to the side wall B and provide supports for the protruding parts 74. The usual spring 41 is provided to maintain the parts 74 and members 77 in engaged relation.

In the modification shown in Fig. 9, the supporting members 85 depend from and are secured to the refrigerant container E. Recesses 86 are formed by upwardly facing hooks on the lower ends of the members 85. The drip pan K has protruding parts 88 secured thereto and upstanding therefrom, the parts having formed thereon downwardly facing hooks 89 arranged to engage with the recesses 86. The spring 41 maintains the hooks 89 and recesses 86 in engaged relation.

Fig. 10 is similar to Fig. 9 except that the supporting members 93 are attached to the inner side wall posts 11 rather than to the container E. Fig. 10 includes, in addition, a bearing member 94 attached to the bottom 43 of the container E and interposed between the bottom 43 and the spring 41 to prevent excessive wear on the bottom of the container. The bearing member 94 may be made of metal, wood or a composition, such as masonite.

In Figs. 11-13, the edge of the drip pan K adjacent the side wall B of the car is supported by recessed supporting members 28 as shown in Fig. 1. The spring for maintaining the protruding part 32 of the drip pan K engaged with the recesses 29 comprises a horizontally extending part 97 secured at its central portion to the inner posts 11 of the car and having a semi-circular leaf spring 98 formed on each end thereof. The springs 98 exert a downward force upon the drip pan K. The edge of the drip pan K adjacent the center of the car is supported by a hook 100 similar to the hook 59 shown in Fig. 6 except that the recess 101 in the partition L is on the opposite side thereof. The hook 100 is maintained in engaged relation with the strip 103 by a double leaf spring 104 attached to the partition L and having both ends 106 bearing upon the drip pan K to exert a downward force thereon. Resilient material 107 is secured to the lower edge of the partition L to prevent leakage of liquid into the lading compartment R of the car.

In Figs. 14 and 15, an angle shaped clip 110 is attached to the inner side wall post 11 and a pin 111 depends from and is rigidly secured to the horizontal leg 113 of the clip 110. The drip pan K has a U-shaped member 114 secured to the upper surface thereof and the upper leg 116 of the member 114 has a hole adapted to fit over the pin 111. A double leaf spring 117 secured at its center to the drip pan K and interposed between the drip pan K and the upper edge of the lining 15 exerts an upward force upon the drip pan K and keeps the U-member 114 engaged with the pin 111. The drip pan is removed by exerting a downward pressure thereon sufficient to compress the spring 117 and disengage the U-member 114 from the pin 111.

In the modification shown in Fig. 16, the edge of the drip pan K which is adjacent the side wall B of the car is supported as shown in Fig. 1. The partition L is secured to the carlines 17 by angle clips 18 and the drip pan K is hinged to the partition L by a hinge arrangement 120 designed to permit horizontal lateral movement of the drip pan K toward the center of the car sufficient to allow the edge 121 of the drip pan K to clear the side wall lining 15. Such a hinge arrangement is disclosed and described in co-pending West application Serial No. 315,467 filed January 25, 1940. A spring 41 is provided to maintain the protruding part 32 of the drip pan K engaged with recesses 29 of the supporting members 28 and a locking pin 123 is provided in the hinge 120 to prevent the swinging thereof.

In Fig. 17 the partition L and the drip pan

5 K are made integral and the hinge 125 comprises a strap 126 having the upper end pivoted to the carline 17 and the lower end pivoted to the partition L. The strap 126 is inclined so that when the protruding part 32 of the drip pan K is disengaged from the recesses 29 of the supporting members 28, the entire drip pan and partition assembly 128 may be moved laterally toward the center of the car until the edge 121 of the drip pan K clears the lining 15 and then rotated downwardly about the hinge 125.

10 In Fig. 18 the partition L is rigidly attached to the carlines 17 and the drip pan K is hinged to the partition L by a simple hinge 133. The upper part 134 of the lining 15 is hinged (136) 15 to the fixed parts 137 of the lining and arranged to be swung downwardly within the car about a horizontal axis. The drip pan veneer 25 has a depending part 139 and a clip 140 is provided on the lower surface of the drip pan K which have 20 inserted between them the upper edge of the hinged part 134 of the lining 15. In order to lower the drip pan K, it is necessary that it be moved upwardly about the hinge 133 against the compressive force of the spring 41 until the hinged part 134 of the lining 15 is free to swing 25 180 degrees about the hinge 136 into a depending position. The drip pan K may then be rotated downwardly about the simple hinge 133.

25 In the modification shown in Fig. 19, the partition L is also rigidly attached to the carline 17 and the drip pan K is hinged by a simple hinge 133 to the partition L. The side wall lining 15 has attached thereto a latch 145 formed by a vertically disposed plate 146 flared toward the lading compartment R so as to provide a seat 148 for supporting the edge 149 of the drip pan K. The spring 41 interposed between the drip pan K and the container E holds the drip pan K seated upon the latch 145. The drip pan K is swung downwardly by compressing the latch plate 146 toward the wall B of the car. A sliding piece 151 is provided to deflect liquid from the drip pan K to the side wall flue G, the sliding piece 151 being held in position by the helical spring 152.

30 The modification shown in Figs. 20 and 21 is similar to that shown in Fig. 16 except for the means of hinging the drip pan K to the partition L. The pin 155 is supported below the partition 35 L by the strap 156 attached to the partition. A notch 159 is cut in the edge of the drip pan and facing channels 158 are provided on the edges of the notch 159. The pin 155 extends between and is journaled in the channels 158 so that 40 the drip pan K may be either rotated about the pin 155 or moved laterally, in which latter case the pin 155 rolls in the channels 158.

45 In the modification shown in Figs. 22 and 23, the edge of the drip pan K adjacent the side wall B of the car is supported as shown in Fig. 1 and the edge remote from the side wall B is supported as in Fig. 5. The springs 165 for maintaining the supporting means in engaged relation are interposed between the drip pan K and the carlines 17. As shown at the left of Fig. 23, a double leaf spring 166 is attached to the carline 17 and each end 168 of the spring 166 bears on the upper surface of a drip pan K to exert a downward force thereon. To the right of Fig. 23, a helical spring 169 is shown interposed between the drip pan K and the carline 17.

50 The accompanying drawings illustrate the preferred form of the invention, though it is to be understood that the invention is not lim-

ited to the exact details of construction shown and described, as it is obvious that various modifications thereof within the scope of the claims, will occur to persons skilled in the art.

I claim:

1. In a refrigerator car having a roof, a wall and a refrigerant container below said roof, the combination of a drip pan below said container, a supporting member rigidly supported within the car, said drip pan having a part arranged to engage with said member to provide a support for the drip pan, and a spring arranged to yieldingly hold said part and said member in engaged relation.

2. In a refrigerator car having a roof, a wall and a refrigerant container below said roof, the combination of a drip pan below said container, a supporting member having a recess rigidly supported within the car, a part protruding from said drip pan and arranged to nest in said recess to provide a support for the drip pan, and a spring arranged to yieldingly hold said part in nesting relation with said recess.

3. In a refrigerator car having a roof, a wall and a refrigerant container below said roof, the combination of a drip pan below said container, a supporting member rigidly supported within the car, said drip pan having a part arranged to engage with said member to provide a support for the drip pan, and a spring interposed between said container and said drip pan and arranged to yieldingly hold said part and said member in engaged relation.

4. In a refrigerator car having a roof, a wall and a refrigerant container below said roof and adjacent said wall, the combination of a drip pan below said container, a supporting member secured to said wall, said drip pan having a part arranged to engage with said member to provide a support for the drip pan, a spring arranged to yieldingly hold said part and said member in engaged relation, and means to support the edge of said drip pan remote from said part.

5. In a refrigerator car having a roof, a wall and a refrigerant container below said roof and adjacent said wall, the combination of a drip pan below said container, a substantially vertical partition disposed adjacent the side of the container which is remote from said wall, a supporting member secured to said partition, said drip pan having a part arranged to engage with said member to provide a support for the drip pan, a spring arranged to yieldingly hold said part and said member in engaged relation, and means to support the edge of said drip pan remote from said part.

6. In a refrigerator car having a roof, a wall and a refrigerant container below said roof and adjacent said wall, the combination of a drip pan below said container, a substantially vertical partition disposed adjacent the side of the container which is remote from said wall, supporting members secured to said wall and to said partition, said drip pan having parts arranged to engage with said members to support the drip pan, and a spring arranged to yieldingly hold said parts and said members in engaged relation.

7. In a refrigerator car having a roof, a wall and a refrigerant container below said roof and adjacent said wall, the combination of a flue associated with said wall and separated from the interior of the car by a lining, a drip pan below said container arranged to direct fluids into said flue, a supporting member secured to said lining,

said drip pan having a part arranged to engage with said member to provide a support for the drip pan, a spring arranged to yieldingly hold said part and said member in engaged relation.

5 8. In a refrigerator car having a roof, a wall, a refrigerant container below said roof and car-line members adjacent the ends of said container, the combination of a drip pan below said container, a supporting member rigidly supported within the car, said drip pan having a part arranged to engage with said member to provide a support for the drip pan, and a spring interposed between one of said carlines and said drip pan and arranged to yieldingly hold said part and said member in engaged relation.

15 9. In a refrigerator car having a wall, a roof, a refrigerant container below said roof and adjacent said wall, and a substantially vertical partition disposed oppositely of said container from said wall, the combination of a drip pan below said container and extending substantially between said wall and said partition, hinge means arranged to attach said drip pan to said wall and spring actuated latching means arranged to attach said drip pan to said partition.

20 10. In a refrigerator car having a wall, a roof, a refrigerant container below said roof and adjacent said wall, and a substantially vertical partition disposed oppositely of said container from said wall, the combination of a drip pan below said container and extending substantially between said wall and said partition, hinge means arranged to attach said drip pan to said partition, and spring actuated latching means arranged to attach said drip pan to said wall.

25 11. In a refrigerator car having a roof, a refrigerant container below the roof, a drip pan below said container, and a spring associated with said drip pan, said drip pan and said spring being arranged and associated with other parts of the car so that the drip pan is yieldingly retained in position and so that the drip pan may be removed from position upon yielding of said spring.

30 12. In a refrigerator car having a roof, a refrigerant container below the roof, a drip pan below said container, and a spring, said drip pan and said spring being arranged and associated with other parts of the car so that the drip pan is yieldingly retained in position and so that the drip pan may be removed from position upon yielding of said spring.

35 13. In a refrigerator car including a refrigerant container, the combination of a drip pan below said container and spring actuated latching means for supporting said drip pan.

14. In a refrigerator car including a refrigerant container, the combination of a drip pan below said container, interengaging members carried by said car and drip pan respectively, and means to yieldingly hold said members in engagement.

40 15. Means to support a drip pan within a refrigerator car comprising interengaging members carried by said car, and drip pan respectively, and means to yieldingly hold said members in engagement.

45 16. In a refrigerator car having walls, roof and floor which define a lading compartment, a refrigerant container below the roof and above the lading compartment, a vertically extending flue associated with one of said walls, a drip pan below said container having a depending edge engaged in overlapping relation with a part of one of the walls enclosing said flue to direct liquid

into said flue, interengaging supporting members carried respectively by the car and drip pan, and means to yieldingly hold said members in engagement.

17. In a refrigerator car having walls, roof and floor which define a lading compartment, a refrigerant container below the roof and above the lading compartment, a vertically extending flue associated with one of said walls, a drip pan below said container having a part engaged with a part of one of the walls enclosing said flue to direct liquid into said flue, interengaging supporting members carried respectively by the car and drip pan, and means to yieldingly hold said members in engagement, said means being disposed entirely above the lower surface of said drip pan so as not to encroach upon said lading compartment. 5 10 15

18. In a refrigerator car having walls, roof and floor which define a lading compartment, a refrigerant container below the roof and above the lading compartment, a vertically extending flue associated with one of said walls, a drip pan below said container having a part engaged with a part of one of the walls enclosing said flue to direct liquid into said flue, interengaging supporting members carried respectively by the car and drip pan, and means to yieldingly hold said members in engagement, said means being disposed entirely within the space between said container and said drip pan so as not to encroach upon said lading compartment.

WALLACE E. BAILLIE.

CERTIFICATE OF CORRECTION.

Patent No. 2,275,717.

March 10, 1942.

WALLACE E. BAILLIE.

It is hereby certified that the above numbered patent was erroneously issued to "Standard Railway Refrigerator Company, of Chicago, Illinois, a corporation of Delaware" whereas said patent should have been issued to --Standard Railway Devices Company, a corporation of Delaware--, as shown by the record of assignments in this office; and that the said Letters Patent should be read with this correction therein that the same may conform to the record of the case in the Patent Office.

Signed and sealed this 12th day of May, A. D. 1942.

(Seal)

Henry Van Arsdale,
Acting Commissioner of Patents.
